UNITED STATES PATENT OFFICE.

ALFRED WILLIAM SIMPSON, OF UPPER MONTCLAIR, NEW JERSEY.

CONCEALED OPERATING MECHANISM FOR CASEMENT-WINDOWS.

1,249,220.

Specification of Letters Patent.

Patented Dec. 4, 1917.

Application filed March 31, 1917. Serial No. 158,950.

To all whom it may concern:

Be it known that I, ALFRED WILLIAM SIMPSON, a citizen of the United States, residing in Upper Montclair, in the county of 5 Essex and State of New Jersey, have invented certain new and useful Improvements in Concealed Operating Mechanism for Casement-Windows, of which the following is a full and clear specification.

10 The object of the present invention is to provide simple and effective means entirely concealed from view, for operating casement windows. It has been proposed to provide partially concealed operating mechanism for such windows, but so far as I am aware a completely concealed and successfully operating mechanism for casement windows that will fit in with the artistic finish of a room has not heretofore been produced. In the 15 improved mechanism which I have devised all parts of the mechanism extending from the pivoted hanging stiles of the vertically hung casement sash to the operating handle are entirely concealed from view, the handle 20 25 alone being presented upon the inside of the window frame that is as inconspicuous as the knob on a door.

The improved casement window operating mechanism comprises arms or levers rigidly 30 connected with and projecting from the lower pivot pintles of the sash hanging stiles (which, in the usual construction, are supported in closely fitting recesses in the window frame), a centrally pivoted tubular lever 35 connected at its opposite ends through rods or links with the rock arms of the casement pintles and an extensible rod telescoping with said pivoted tubular lever and formed at its inner end with a detent which 40 co-operates with a suitable stationary rack and has at its outer end a suitable knob or handle presented through a slot in the apron of the window sill in convenient position for operation. All of the parts of 45 the described mechanism excepting only the handle are mounted below the sill of the window frame, entirely concealed from view. The locking rack and co-operating dog or detent are of peculiar construction, the rack 50 having forwardly presented angular teeth separated by downwardly expanding dove-tailed recesses, while the locking dog or detent is shaped to snugly fit the dove-tailed recesses, it being of dove-tailed shape in ver-

tical cross section, with an angular nose to 55 properly guide it into engagement with the selected locking recess of the rack.

In order that my invention may be fully understood it will first be described with reference to the accompanying drawings and 60 afterward pointed out more particularly in the annexed claims.

Figure 1 is an inside elevation of window frame equipped with a pair of outwardly opening vertically hung casement windows 65 to which my invention has been applied;

Fig. 2 is an enlarged horizontal sectional view showing the improved concealed operating mechanism for the same. In this view the windows are shown in top plan, while 70 the sill of the frame is entirely removed to expose the improved operating mechanism;

Fig. 3 is a detail plan view, partly in section, of the main portion of the operating mechanism, this view being on a still larger 75 scale for the purpose of clearness;

Figs. 4 and 5 are detail sectional views of parts hereinafter referred to.

In the window frame shown at 1, the two outwardly opening casement windows 5, 10, 80 are hung upon their hanging stiles by means of pivot pintles projecting above and below and having bearings, as usual, in suitable sockets sunk in the top and bottom rails of the window frame. The side rails of the 85 window frame are recessed, as shown at 2, in Fig. 2, to snugly fit around the angular edges of the hanging stiles.

Suitably secured to the downwardly projecting pivot pintles of the sashes 5 and 10 90 are rock arms indicated at 15 and 16, to which are respectively connected the rigid rods or links 20 and 21, pivoted at 25 and 26, upon the open ended tubular lever member 30. This member 30, which constitutes a 95 double lever for operating the connected casement windows is preferably formed with a central bracket lug 31, having a pivot pin 32, projecting from it midway between the ends of the tubular member 30. This 100 pivot 32 is properly journaled in an opening formed in a bracket plate 35, having secured to it a locking rack 36, hereinafter more specifically described.

The tubular lever 30 carries extension rod 105 40, which telescopes with the member 30 and is preferably provided with a stop pin 41, operating in a longitudinal slot 33, of

member 30, to limit the movement of the rod 40 outwardly in member 30. A spring 44 may be mounted between the rod 40 and tubular member 30, as shown in Fig. 3, to afford a slight resistance to the relative movement between these parts so that the rod will remain where it is placed by the operator. The outer end of the extension rod 40 is formed with a knob or handle 45 which may be integral with the rod 40 or be detachably secured thereto like the ordinary door knob is secured to its shank.

The bracket plate 35 is formed with the curved rack 36 having a series of ribs or teeth 36^a, formed with outwardly presented angular noses and separated by recesses 36^b of corresponding shape, but of dove-tailed cross section with the widening of the recesses extending downwardly from the upper face of the rack. The inner end of the expansible rod 40 is shouldered down to form a locking dog or detent 43 of the size and shape to accurately fit the dove-tailed recesses 36^b of the locking rack, so that the rod can be pushed inwardly with the detent 43 projecting beyond the end of lever 30 into engagement with the desired recess of the rack to hold the mechanism in the desired adjusted position.

30 In the described mechanism the bracket 35, carrying the rack 36 and supporting the pivoted operating mechanism is suitably mounted in the base of the window frame directly beneath the window sill, the extensible rod 40 projecting through a horizontally arranged slotted escutcheon plate 50, fastened in the apron of the sill, as shown. When arranged in this manner the only part of the mechanism, which is in view is the 40 knob or handle upon the operating rod and the face of the escutcheon plate, through which it operates.

The operation of the mechanism will be understood from the following explanation:

45 In Figs. 1 and 2 of the drawings the windows are shown open approximately 45°. In this position the operating mechanism is in its central location. If it is desired to close the windows, the operator grasps the handle 45 and pulls the rod 40 outwardly to disengage the dog 43 from locking recesses 36^b of the rack. When the rod is pulled out to its limit to release the mechanism and afford an extended lever, the 55 operator pushes the lever to the right, causing the two windows to be closed, and then pushes the rod 40 inwardly until the dog 43 engages a new notch in the locking rack when the mechanism will be securely held 60 with the window closed. With this mechanism the windows can be securely held in any desired position whether fully open, fully closed or at any point between these extremes. Because of the effective engagement between the locking dog and rack (the

engaging parts being dove-tailed) there is no danger of the mechanism coming loose nor of the windows rattling by reason of the wind. The arrangement of all the operating mechanism below the window sill, enables 70 the architect to embody this highly artistic casement window in his design without interference or marring by the use of clumsy operating mechanisms and attachments which have heretofore been employed in connection with such windows. The operating handle 45 upon the rod 40 may be of any suitable shape or design to fit and correspond with the finish of other hardware, like the door knob, for instance. 75

I have shown the mechanism arranged for a pair of outwardly opening casement windows, but it will be clear that a single window can readily be operated by the improved mechanism, in which case one of the connecting rods 20 or 21 and its attached rock arm 15 or 16 would be omitted. The mechanism would otherwise be the same as illustrated and described.

I claim:

1. In a device of the character described, the combination of a casement window pivoted upon its hanging stile, a rock arm projecting from the window pivot, a rod extending from said rock arm, a lever to which said rod is connected, a locking device for securing said lever in the desired adjusted position, and an extensible member carried by said lever projecting through a slot in the window frame, said lever, locking device, rod and rock arm being concealed in the window frame. 90

2. In a device of the character described, the combination with a pair of outwardly opening casement windows pivoted upon their hanging stiles, of rock arms projecting from the window pivots, rods pivotally connected with said rock arms, a pivoted operating lever pivotally connected with said rods, means for locking said lever against movement, said rock arms, rods, operating lever and locking means being concealed within the window frame, and an operating handle projecting from said operating lever through the window frame. 100

3. In a device of the character described, the combination of a suitable bracket plate formed with a locking rack, an open ended tubular lever pivotally mounted upon said bracket plate, an extension rod telescoping with said tubular lever and formed at one end with a dog or detent projecting normally beyond the end of the lever and adapted to engage said rack, said extension rod having at its other end an operating handle, a pivotally mounted window, and operating mechanism extending from said window to said tubular lever. 120

4. In a device of the character described, the combination of a pivotally mounted tu- 130

tular lever, a locking rack fixed with relation to said lever, an extension rod telescoping with said tubular lever and formed at one end with a dog or detent adapted to engage said rack and at its other end with an operating handle, said rack having a series of teeth separated by dove-tailed recesses and said dog or detent being of dove-tailed cross-section to fit said recesses, a pivotally mounted window and operating mechanism 10 extending from said window to said tubular lever.

ALFRED WILLIAM SIMPSON.
